UNITED STATES PATENT OFFICE.

FREDERICK HACHMANN, OF MILWAUKEE, WISCONSIN, ASSIGNOR OF THIRTY-ONE FORTIETHS TO M. F. ELISABETH BAASEN AND HENRY L. STROHMEYER, OF SAME PLACE.

MEANS FOR BONDING RAILWAY-RAILS.

SPECIFICATION forming part of Letters Patent No. 617,737, dated January 17, 1899.

Application filed September 14, 1898. Serial No. 690,959. (No model.)

To all whom it may concern:

Be it known that I, FREDERICK HACHMANN, of Milwaukee, in the county of Milwaukee and State of Wisconsin, have invented a new and useful Improvement in Means for Bonding Railway-Rails, of which the following is a description, reference being had to the accompanying drawings, which are a part of this specification.

10 My invention relates to bonding or coupling together the abutting ends of railway-rails, and because my invention is especially applicable to the rails of street-railways I show in my drawings herewith a style of railway-rail substantially such as is in common use, which being somewhat changed in making is adapted for the application of my invention thereto.

15 The invention consists of the means, in combination and in segregation, for bonding together railway-rails, as herein described and claimed, or their equivalents.

20 In the drawings, Figure 1 is a vertical longitudinal section of adjacent portions of the abutting ends of railway-rails, showing therewith my improved means, partly in section, for bonding the rails together. Fig. 2 is a top plan view of the abutting ends of two railway-rails and my improved bonding means 25 applied thereto. Fig. 3 is an end view of the street-railway rail illustrated in Figs. 1 and 2, shewing the thickened portion of the web of the rail near its end required for applying my improved bonding means and the bonding device in cross-section. Fig. 4 is a perspective view of my improved rail-bonding device. Fig. 5 is a perspective view of a plug employed in securing my improved bonding device in position on the ends of the rails.

30 A street-railway rail as now constructed is formed with a foot 10, a web 11, a laterally-projecting top tread 12, and a somewhat lower and oppositely-projecting flange or ledge 13. To apply my improved bonding device to rails of substantially this form, it is necessary to provide somewhat enlarged or thickened ends of the rails, and for this purpose the rails are constructed with a boss or thickened web 14, extending from the foot 10 to the tread 12 and from the end of the rail

along the rail endwise a few inches, substantially as shown in Figs. 1 and 3.

The bonding device employed by me consists of a bar or elongated body 15, having a substantially flat top surface and provided at its respective ends with downwardly-extending legs 16, the extremities or free ends of which are enlarged, both projecting laterally in the same direction and preferably in the direction of the long axis of the bar or body of the device, forming a projecting toe 17. These legs are preferably severally inclined or beveled on the side of the toe 17 from the junction of the leg with the body of the device to the extremity of the toe, forming the oblique wall or surface 18. The wall of the leg opposite the beveled wall 18 is advisably transversely recessed, as shown at 19. For applying this bonding device to the abutting ends of the rails a longitudinal recess is cut in the tread 12 of the rails of such size and form as to receive the body 15 of the bonding device therein, and deeper recesses or sockets are cut in the rails, respectively, at the ends of the elongated recess or channel 20 to admit therein the legs 16 of the bonding device. These sockets in the rails are undercut in such direction as substantially to be complementary to the beveled surfaces 18 when the bonding device is applied to the 25 rails, and the sockets in the rails in which these legs 16 are inserted, while being substantially of the same width transversely as the width of the legs 16, are elongated in the other direction sufficiently to permit of the 30 ready insertion of the enlarged extremities of these legs 16 into the sockets. In applying my bonding device to the abutting ends of two rails provided with such channels and sockets the legs 16 are inserted in the sockets 35 in the rails, the body 15 being in the channel therefor in the tread of the rail, and thereupon the bonding device is pushed endwise in its seat, carrying the projecting toe portions 17 of the legs under the overhanging 40 portions of the rails in the manner shown in Fig. 1, bringing the beveled surfaces 18 below and opposite correspondingly-undercut surfaces of the rail or walls of the sockets. Thereupon the plug 20 is inserted in the re- 45

cess in the rail at the rear end of the bonding device, filling the aperture in the rail at the surface of the tread and locking the bonding device in place in the ends of the rail. 5 Thereupon molten metal is poured through an aperture 21 in the plug 20 into the space in the socket in the rail about the leg 16, which molten metal 23 passes beneath the extremity of the leg and about its toe and into the recess 19 and fills up the socket about and on either side of a tongue 22, projecting medially from the under side of the plug 20. As this metal sets and hardens it forms with the legs 16 and the plug 20 a key that secures the bonding device firmly in the end of the rail. At the other extremity of the bonding device molten metal is poured through the aperture 24 in the body of the bonding device into the space in the rail-socket about 20 the leg 16 therein, and when this molten metal 23 sets and hardens therein this extremity of the bonding device is thereby locked firmly in the end of this rail.

The bonding device is so constructed and 25 fitted into the ends of the rails that its top surface is flush with the surface of the tread of the rails, whereby a smooth and continuous tread-surface is formed along on the rails and from one rail to the other. The sides of 30 the tongue 22 of the plug 20 are preferably made concave, so that the free edge of the tongue is wider than its medial portion, thus forming a key-like construction that cannot be removed from the metal that was poured 35 into the socket and has hardened about it.

What I claim as my invention is—

1. The combination with abutting railway-rails having a recess in the tread of each rail at the abutting ends thereof and sockets each 40 with an overhanging wall in the rails at the inner ends of the recesses, of a bonding device having a bar-like body fitted in said recesses and terminal legs with toes projecting laterally in the same direction inserted in said 45 sockets the toes being under the overhanging walls of the sockets, and means locking said bonding device in place in the rails.

2. The combination with the abutting ends of two railway-rails provided with registering recesses in the treads of the rails and sockets 50 having undercut walls in the rails at the inner extremities of the recesses, of a bar-like bonding device fitted in said recesses, and legs on the extremities of said bar having projecting toes, said legs being inserted in said 55 sockets the toes under the overhanging walls of the sockets, a plug in the recess at the end of the bonding device holding the bonding device in place, the toes of the legs under the overhanging walls, and metal fillings introduced in molten state into the sockets about 60 the legs securing the parts in position.

3. A bonding device for bonding together railway-rails, consisting of an integral metal bar and legs thereon one at each extremity 65 of the bar projecting in the same direction, the legs having laterally-projecting toes on corresponding sides of the legs.

4. An integral bonding device for bonding together railway-rails, comprising an elongated bar, legs at the ends of the bar projecting therefrom on the same side of the bar, the legs each having a beveled side wall, an enlarged free end projecting laterally in the same direction, and a recess in the wall opposite the beveled wall. 70

5. A railway-rail provided with recesses one at each end in the tread of the rail extending in the direction of the length of the rail from its ends inwardly a distance, and provided 80 with sockets entering deeper into the rail one at or near the end of each of said recesses and continuous therewith, said sockets each having an undercut wall, the undercut walls of the sockets projecting in the same direction 85 whereby two abutting rails may be securely bonded to each other by a conforming bonding-piece.

In testimony whereof I affix my signature in presence of two witnesses.

FREDERICK HACHMANN.
